GRINDING

John A. Cupler, II, Cumberland, Md.

Application September 24, 1946, Serial No. 699,003

4 Claims. (Cl. 51—103)

1

Apparatus and methods for grinding currently in use, are largely dependent upon the accuracy of bearings, centers, regulating wheels and grinding wheels provided by the equipment for the ultimate tolerances attainable. Grinding contemplated the use of chucks or centers of the ordinary type, necessitate rotation of the work about the axis of an element which is not necessarily the axis of the work. Even in centerless grinding, it is customary to permit the work to float between a grinding wheel and a regulating wheel, in conjunction with which a support is frequently employed. In such centerless grinding techniques however, the work is again not necessarily maintained with its own axis aligned throughout the operation, since imperfections in the surfaces of the grinding wheel, the regulating wheel and/or the support will vary the position of the work axis, as will any imperfections or eccentricities transmitted to any of these elements from their drives.

Whereas the development of the art has witnessed vast improvements, particularly during recent years, existing techniques will not permit the holding of such tolerances as are required for example in the production of drills having cutting portions whose diameters are of the order of up to several thousandths of an inch.

In accordance with the present invention, it is sought to provide apparatus and procedure adapted for the maintenance of such close tolerances, whether for the production of so-called microscopic drills and punches or for larger types of work in connection with which concentricity and overall accuracy are desired.

This invention is particularly applicable for use on a work piece having a cylindrical surface and a second surface to be rendered coaxial therewith and is applied by peripherally driving the work piece about its cylindrical axis and simultaneously holding the work piece against axial displacement while operating on the surface to be rendered coaxial. The work support may provide a notch or bight, or a plurality of spaced notches or bights to receive a cylindrical portion of the work, such bights being defined for example by spaced pairs of elements defining substantially point contact for the work such as would be produced by spherical sections of relatively hard materials such as certain types of steel, or synthetic or natural diamonds or sapphires. The work is preferably rotated by a means frictionally engaging its periphery, such as a roller which may be grooved to form lands so as to maintain the work in the one or more notches or bights provided by the supporting means to assure its constant axial position during an operation. Where the driving roller is provided with lands, they are preferably spaced to substantially correspond with the spaced sup-

porting elements, thereby reducing bending tendencies.

The supporting means for the work is preferably so disposed with respect to the axis and direction of rotation of the driving means that upon engagement of the driving means with the work, the latter is biased towards a stop whose position may be adjusted so that the axial position of the work piece will be established at the beginning of an operation and maintained throughout the operation. This result may be produced by a relatively small displacement of the axes, which may exist with respect to only a single plane. The work engaging means or driving roller is preferably supported for swinging movement about a remote axis to permit insertion and removal of work with facility, the drive for the roller being so arranged that its rotation can continue even while it is disengaged from the work piece.

The work piece supporting means or compound is preferably adjustable with respect to a plurality of axes so that the work piece can be assigned any one of a plurality of positions with respect to a tool. Such adjustment may be rectilinear in some cases and arcuate in others, depending upon the desired relationship to be established between the work piece and the tool. Where the invention is applied to operations with drills or rotary reamers for example, the shank of such element is preferably cylindrical for cooperation with the supporting means and frictional engaging means, the cutting portions of the element projecting beyond the frictional engaging means to operate on a member or be operated on by a tool.

The tool which performs the operation on the work piece may be a grinding wheel, the direction of rotation of which may correspond with that of the frictional engaging means or roll, and the two may be rotated by independent power sources where desired. Means may also be provided for reciprocating the grinding wheel with respect to its own axis and preferably in its own bearing in order to maintain such axis constant in space. The reciprocation of the grinding wheel may be effected by a cam acting upon an extension of the grinding wheel shaft, which cam may be rotated by an independent driving means or a driving means employed for one or both of the grinding wheel and driving roll.

A more complete understanding of this invention will follow from a detailed description of the accompanying drawings wherein:

Fig. 1 is a plan of apparatus in accordance with the present invention;

Fig. 2 is a front elevation partially in section 60 of the apparatus shown in Fig. 1;

Fig. 3 is a sectional elevation taken along line 3-3 of Fig. 1;

Fig. 4 is an elevation, partially broken away, showing the right end of the apparatus of Fig. 2;

Fig. 5 is an elevation of a portion of the work piece support, enlarged for greater detail; and

Fig. 6 is a plan of the portion of the work piece support depicted in Fig. 5.

The apparatus has been depicted in the drawings as supported upon a base or table 10 by means of a grinding wheel frame 12 and a compound pedestal 14. The grinding wheel frame accommodates a pair of spaced bearings 16 secured therein by cooperating sleeves 18 and 20, the former of which is threaded to receive a nut 22 for drawing the complementary frustoconical surfaces of the sleeves into binding relationship. The grinding wheel shaft 24 is received in these bearings for rotation by means of a pulley 26 fixed to a reduced extension 28 thereof and driven by a belt 30 from a motor 32 located below the table, and reciprocated therein by means of a cam 34 bearing against a ball 36 received in a bore 38 formed in the reduced end of the shaft. The opposite end of the shaft 24 is provided with a similar bore 40 which receives a ball 42 for bearing against a plunger 44 telescopically received in a sleeve 46 and biased against the ball 42 by means of a coil spring 48 whose other end bears upon a reduced shoulder 50 in the sleeve. The sleeve 46 is supported in a bracket 52 suitably mounted on the table 10, a suitable key or set screw 54 in the bracket cooperating with a keyway 56 formed in the outer surface of the sleeve to prevent relative movement of the sleeve with respect to its brackets. The plunger 44 is provided with a reduced portion 58 projecting entirely through the sleeve and terminating in a threaded portion 60 for receiving a limiting nut 62 and a lock nut 64.

The cam 34 is fixed to a shaft 66 which is driven by means of a motor 68, pulley 70, belt 72, pulley 74 and gear reduction box 76, the details of which have not been illustrated.

An enlarged section 78 of the shaft 74 receives a pair of threaded collars 80 and 82 provided with cooperating threads 84 for clamping the opposed radial surfaces of the collars against the two radial surfaces of a grinding wheel 86. The grinding wheel being thus fixed with respect to its shaft, will partake of the rotary movement imparted to the shaft through the pulley 26 of an axial reciprocating movement imparted thereto by the cam 34. It will be clear that the relative rates of these two movements may be varied to suit the requirements of different types of work, different types of grinding wheels and other factors which may be encountered. It will also be clear that the shape of the cam may be modified to produce different modes of reciprocation. The bearings and their retaining sleeves have been depicted as having radial ports through which lubricants may be introduced from suitable sources 88 which have been depicted as of the adjustable type well known in the art. Moreover, a stationary tool may be employed.

These lubricators 88 are shown as threadedly received in bearing caps 90 secured to the frame by suitable bolts 92.

Mounted on the table 10 behind the grinding wheel, there is provided a compound 94 having a longitudinal slide 96 adjustable by means of a thumb screw 98, upon which is mounted a transverse slide 100 adjustable by means of a thumb

screw 102 to position a diamond type or other suitable wheel dressing material when it is desired to true the grinding wheel or modify its contour.

A compound 104 supported on the pedestal 14 is rendered arcuately adjustable by means of a pair of screws 105 whose threaded ends are recessed to receive balls 108 applied against a bearing lug 110 projecting forwardly from a table 111 integral with the pedestal. The screws 105 are carried by a plate 113 which is suitably attached to an arcuately adjustable slide 115 to provide for arcuate adjustment of the work piece with respect to the table 111. A longitudinal slide 112, adjustably supported by the slide 115, may have its position adjusted by manipulation of a screw 114 and a superposed transverse slide 116 is adjusted by means of a screw 118. The transverse slide 116 in turn supports a plate 120 which is rendered vertically adjustable with respect thereto by means of a wedge 122 which is advanced or retracted by means of a screw 124, contact between the wedge and plate being maintained under the force of a spring 126 engaging the head of each of the one or more bolts 128 extending through the plate 120 into the transverse slide. A work piece holder or support 132 is received in a sleeve 134 carried by the plate 120 and retained therein by means of a set screw 136. One end of the work piece support is threaded to receive a screw 136 having a reduced end 138 which functions as a stop for the work piece 140, a head 142 for adjustment of the stop and a locking nut 144 to maintain the stop against accidental movement.

As depicted in Figs. 5 and 6, the work supporting portion of the member 132, corresponding with the right hand portion of Fig. 2, has a substantially plane upper surface 146 carrying two spaced pairs of bight forming elements 148 whose substantially spherical or partially spherical surfaces provide four substantially point contacts for the work piece. It will be noted especially with reference to Fig. 6, that in the horizontal plane, a line passing through the bight of the two pairs of balls or the like is slightly angularly displaced with respect to the center line of the work piece support itself. The angular displacement is depicted as being of the nature of two or three degrees, the numerical value of which is not critical so long as it serves to provide a biasing of the work piece against the end of the stop which in assembled relationship occupies a portion of the groove 150 shown in Fig. 6. The manner in which this biasing effect is produced remains to be described.

A pair of brackets 152 serves to journal a frame 154 for pivotal movement with respect to the plate 120 about the axis of a shaft 156 rotatable in the frame. A portion of the shaft 156 extends beyond the frame to receive a bevel gear 158 in mesh with a similar bevel gear 160 carried at the end of a transmission shaft 162 containing a pair of universal joints 164 and 166, the transmission shaft being driven through a gear reduction box 168, a pulley 170, a belt 172, a pulley 174 and a shaft 176 from a motor 178.

The shaft 156 mounted in the frame 154 has a spur gear 180 secured thereto through which it drives a similar gear 182 secured to a parallel shaft 184 likewise journaled in the frame 154. An end of the shaft 184 projects through a side of the frame 154 to receive on its end, a roller 186 whose periphery is provided with a groove 188 defining lands 190 which are spaced in sub-

stantial correspondence with the spacing between the pairs of bight forming elements 148 arranged therebelow on the work supporting member 146. The surface of the roll 186 may be defined by a friction material such as a rubber composition or any other type of friction surface such as would be provided by a fine grit grinding wheel, having a plain or grooved periphery so that when its edge engages the periphery of the work piece, the latter will be rotated in a direction opposite to that of the roll, the roll and the grinding wheel 86 preferably having the same direction of rotation. Inasmuch as the axis of the shaft 184 and the roll 186 is parallel with the axis of the work piece support 132 as depicted in Fig. 6, the roll axis will be slightly displaced from the work piece axis because of the arrangement of the bight forming elements, whereby rotation of the roll in contact with the periphery of the work piece will bias the end of the work piece against the stop 138 so as to position the work piece axially during a grinding operation.

When it is desired to insert a work piece in the apparatus, the frame 154 can be lifted by means of its handle 192 to swing about the axis of the shaft 156, whereupon the work can be introduced between the bights of the supporting elements, the slot 194 shown in Fig. 6 as formed in the work support between the pairs of bight forming member, facilitating the introduction and removal of a small piece of work by means of tweezers or the like, or a larger piece of work by a correspondingly larger and suitable implement or by the hand of the operator.

Having inserted a work piece, the frame 154 can then be lowered to the position shown in the drawings whereupon the lands of the roll will engage the periphery of the work piece immediately above the bight forming elements to rotate the work piece and drive its end against the stop. The introduction of a work piece is preferably effected while the grinding wheel is at a distant portion of its reciprocating stroke so that by the time the grinding wheel advances sufficiently to engage the work, the work piece will have assumed its rotary motion and will have been biased against the stop.

A suitable coolant may be supplied from a tank and pump assembly 196 arranged below the table and connected by means of suitable tubing 198 with a vertical pipe 200 and through a valve 202 for controlling the flow and suitable fittings to a goose neck 204 which may supply the coolant to the groove of the roller 186 or to some other appropriate point in that vicinity.

It will be clear that by suitable adjustment of the work support compound, a variety of operations can be obtained whereby the apparatus can be used for cylindrical grinding, back taper, flat grinding or facing, and the work can be moved to assume almost any desired angle with respect to the grinding wheel or other tool which may be substituted, and if it is desired to insert a drill on the work support, the type of drive herein described might well be used to perform a drilling operation. The apparatus may be used for operating on many types of work including drills, broaches, punches, and other types which will readily suggest themselves to those skilled in the art. Provisions may be made for driving the various motors at speeds ranging from zero to their maximum values and it is contemplated that the use of known types of transmissions

would permit the use of fewer motors or other power sources.

Whereas but one embodiment of the invention has been described with reference to the accompanying drawings, it is not intended that the invention be restricted thereto beyond the scope of the appended claims.

I claim:

1. Grinding apparatus comprising means providing a plurality of pairs of contacts each fixed with respect to the others for supporting a work piece for rotation about its own axis, means for frictionally engaging peripheral portions of said work piece substantially opposed to said contacts 10 to rotate the same, said supporting means and engaging means providing means to maintain axial alignment of the work piece, a grinding wheel rotatable in a plane displaced from said engaging means for operating on a portion of 20 said work piece projecting beyond said engaging means, and means for driving said engaging means and grinding wheel.
2. Apparatus comprising spaced pairs of elements having substantially spherical surfaces for 25 supporting a work piece for rotation about its own axis, means for frictionally engaging a peripheral portion of said work piece to rotate the same, said supporting means and engaging means providing means to maintain axial alignment of the work piece, a tool disposed in a plane displaced from said engaging means for operating on a portion of said work piece projecting beyond said engaging means, and means for driving said engaging means.
3. Apparatus comprising means providing a plurality of substantially point contacts each fixed with respect to the other for supporting a work piece for rotation about its own axis, means for frictionally engaging a peripheral portion 40 of said work piece to rotate the same, said supporting means and engaging means providing means to maintain axial alignment of the work piece, a tool disposed in a plane displaced from said engaging means for operating on a portion of said work piece projecting beyond said engaging means, and means for driving said engaging means.

4. A method of grinding a work piece having 50 a cylindrical reference surface comprising supporting said reference surface at a plurality of points spaced circumferentially and along the axis thereof, drivingly engaging said surface opposite said points of support to thereby rotate said work piece relative to said points, biasing said work piece to a position axially fixed with respect to said points, and grinding a portion of said work piece.

JOHN A. CUPLER, II.
